CIRCUIT BREAKER

Hans H. Willmann, Berlin-Charlottenburg, Germany, assignor to Westinghouse Electric & Manufacturing Company, East Pittsburgh, Pa., a corporation of Pennsylvania

Application August 2, 1937, Serial No. 157,028
In Germany August 3, 1936

10 Claims. (Cl. 200—88)

The invention relates to circuit breakers in general and more particularly to circuit breakers of the type used for controlling lighting and moderate power distribution network systems, in which the breaker is manually operable to open and to close the circuit and automatically operable to open the circuit in response to predetermined overload conditions.

To be commercially successful, the circuit breaker for such use must be capable of interrupting large amounts of electric power due to the interconnection of the numerous circuits of the system. The trip device of the breaker must be capable of distinguishing between overloads of differing magnitude so that it will open the breaker immediately upon the occurrence of a short circuit condition, and only after a predetermined period of time in response to overloads of moderate magnitude in order to prevent undue interruptions of service in response to transitory lower magnitude overloads. It is desirable that the actuating mechanism of the breaker open and close the contacts with a snap action in order to minimize arcing; and that the contacts be trip-free of the operating handle so that the breaker may be tripped open even though the handle is held in the closed position. The tripping and actuating mechanisms must be extremely accurate in operation and must maintain their accuracy for a considerable period of time. This means that only very small tolerances can be permitted in the manufacture of the breaker. In addition to the above requirements, the circuit breaker must be simple, safe and reliable in operation, compact, and inexpensive to manufacture.

An object of the invention is the provision of an improved circuit breaker that will satisfactorily meet all of the above-mentioned requirements.

Another object of the invention is the provision of a circuit breaker with an improved actuating mechanism for actuating the contact means to open and close the circuit.

Another object of the invention is the provision of a circuit breaker with an improved actuating mechanism which provides for greater safety of operation of the breaker and which prevents improper operation of the same.

Another object of the invention is the provision of an improved actuating mechanism for a circuit breaker for opening the contacts with a snap action, and which is operable to close the contacts with a snap action at a predetermined point in the closing movement of an operating

member regardless of the speed of movement of the member.

Another object of the invention is the provision of a circuit breaker with an improved and simplified tripping mechanism which is manually operable to open the breaker contacts and automatically operable to open the breaker contacts in response to predetermined overload conditions.

Another object of the invention is the provision of a circuit breaker having a casing consisting of several sections suitably recessed to receive the various parts of the breaker, with an improved mounting means for securing the tripping and actuating mechanism and the combined tripping and blowout electromagnet to one of the sections and for securing the several sections together.

Another object of the invention is the provision of a circuit breaker embodying a casing of ceramic insulating material with an improved mounting arrangement for the actuating mechanism in which a base plate mounted within the casing supports the actuating mechanism and is formed to provide stops for the switch lever so as to relieve the casing of impact stresses during operation of the breaker.

Another object of the invention is the provision of an improved circuit breaker that is simple and rugged, safe and reliable in operation, which is extremely compact so that it occupies a relatively small amount of space, and which can be manufactured at a relatively low cost.

The novel features that are considered characteristic of the invention are set forth in particular in the appended claims. The invention itself, however, both as to structure and operation, together with additional objects and advantages thereof, will best be understood from the following detailed description of several embodiments thereof when read in connection with the accompanying drawings, in which:

Fig. 1 is a vertical sectional view of the circuit breaker embodying the features of the invention;

Fig. 2 is a fragmentary view of the breaker with a portion of the casing broken away and parts shown in section to illustrate certain mounting features of the invention;

Fig. 3 is a horizontal sectional view of the breaker shown in Fig. 1 taken on the line III—III thereof and looking in the direction of the arrows;

Fig. 4 is a fragmentary sectional view of the breaker illustrating the actuating mechanism in the open circuit position;

Fig. 5 is a fragmentary sectional view similar to Fig. 4 illustrating a modified form of the actuating mechanism;

Fig. 6 is a diagrammatic view of a slightly modified arrangement of the actuating mechanism shown in Figs. 1 and 4;

Fig. 7 is a fragmentary detail view illustrating the two part switch lever and biasing springs in end elevation;

10. Fig. 8 is a top plan view of the main frame showing the manner in which the supporting lever for the toggle links and the latching lever are pivotally mounted thereon; and

15. Fig. 9 is a fragmentary plan view of the base plate showing the stop means for the switch lever.

Referring to the drawings, the circuit breaker illustrated comprises a casing indicated generally at 11 which consists of an intermediate base section 13, a cover or end section 15 and a supporting end section 17, all of ceramic insulating material. The supporting section 17 is provided with a threaded contact shell 19 of conducting material and a center contact 21 located adjacent the 25 lower end of the supporting section. The contact shell 19 and the center contact 21 form the terminals of the circuit breaker, the breaker being of the type that is supported by an electrical socket which serves to connect the breaker in an 30 external electrical circuit. The supporting section is also provided with a chambered recess 23, in which is disposed an electromagnetic means indicated generally at 25. The electromagnetic means 25 serves to trip the breaker open upon 35 the occurrence of heavy overload currents or short circuit conditions in the controlled circuit and also acts as a magnetic blowout means for moving and extinguishing the arc drawn between the contacts of the breaker during circuit interruption.

The electromagnetic means comprises a coil 27 which is wound upon an insulating spool 29, a stationary core 31 and a cooperating movable core 33, both of magnetic material. The stationary core 31 and the movable core 33 are enclosed by a sleeve 35 disposed within the central opening of the spool 29. The lower end of the sleeve 35 is provided with an inturned flange which limits downward movement of the movable core.

50. An adjusting means is provided for varying the tripping point of the electromagnet 25. The adjusting means comprises an adjusting screw 37 threaded in the movable core 33 and a compression spring 39 disposed between the inturned flange at the lower end of the sleeve 35 and the head of the screw.

The stationary core 31 is provided with a central cylindrical opening through which extends a thrust rod 41, the lower end of the thrust rod extending near the movable core 33 while the upper end of the thrust rod extends through a cylindrical opening provided in the intermediate base section 13. The thrust rod 41 is adapted to be moved upwardly when the movable core 33 is attracted in response to a heavy overload or short circuit condition to trip the breaker open in a manner which will be described hereinafter.

70. The intermediate base section 13 is provided with a recess 43 over the electromagnetic means 25 which forms a switch chamber. Disposed within the switch chamber 43 are a pair of spaced stationary contacts 45 and a movable yoke-shaped bridging contact 47, which cooperates with the 75 stationary contacts to open and close the circuit,

The movable contact 47 is adapted to be moved by the actuating mechanism in a horizontal plane to open and close the circuit through the breaker. It will be noted that the path of movement of the movable contact is at right angles to the axis 5 of the electromagnet 25, so that the magnetic flux produced by the electromagnet acts to move and extinguish the arc drawn between the contacts during circuit interruption.

A base plate 49 is secured to the upper surface 10 of the intermediate base section 13 and covers the switch chamber formed therein. Mounted on the base plate 49 is a main frame 51 consisting of a pair of spaced side plates 53 (Figs. 2 and 8). The lower ends of the spaced plates 53 are bent 15 outwardly at right angles and are adapted to be secured to the base plate 49, as shown in Fig. 2.

The actuating means of the circuit breaker comprises, in general, a pivoted multiple arm switch lever indicated generally at 55 the lower 20 end of which is connected to the movable contact 47, a pair of toggle links 57 and 59, a pivoted supporting lever 61 for supporting one end of the toggle formed by the links 57 and 59, a pivoted latching lever 63 for releasably engaging and restraining the supporting lever in operative position, a closing push button 65 for closing the breaker, and a release push button 67 for opening the breaker, both of insulating material. The supporting lever 61 (Fig. 8) is pivotally supported on the main frame by means of a transverse pivot pin 69, which extends through openings provided therefor in the side plates 53 of the main frame. The lever 61 is provided with an integral U shaped bearing portion 71 extending at right angles to the lever portion 73 thereof. The bearing portion 71 is provided with openings which engage the pivot pin 69 at two bearing points outside of the side plates 53 of the frame, the lever arm 73 of the supporting lever being disposed outside of the main frame. It will be noted that the bearing points of the bearing portion 71 of the supporting lever 61 are spaced apart a greater distance than the effective lever arm 73 40 of the supporting lever.

The toggle links 57 are pivotally connected at one end by means of a pivot pin 75 with the upper end of the multiple arm switching lever 55. The opposite ends of the toggle links 57 are pivotally connected to one end of the toggle link 59 by 50 means of a knee pivot pin 77, while the opposite end of the toggle link 59 is connected to the bearing portion 71 of the supporting lever 61 by means of a pivot pin 79.

The latching lever 63 is pivotally supported on the main frame by means of a pivot pin 80 in substantially the same manner as the supporting lever 61.

The latching lever 63 is provided with a U 60 shaped bearing portion 81 having openings which engage a transverse pivot pin 80 outside of the main frame 51, and an angular lever arm portion 83 disposed outside of the main frame in the same manner as the supporting lever 61. The upper end of the latching lever 63 is notched, as indicated at 85, and engages the free end of the supporting lever 61, as best shown in Fig. 1. The latching lever 63 thus normally serves to hold the supporting lever 61 in a normal or operative 70 position to maintain and support the right-hand end of the toggle in an operative position. The latching lever 63 is adapted to be moved in a counter-clockwise direction about its pivot pin 80 to effect release of the supporting lever 61 to trip 75

the breaker in a manner which will hereinafter be described.

The push button 65 is mounted for vertical movement on the frame 51 by means of upper and lower guide plates 87 and 89 which extend transversely between the side plates 53 of the main frame, the upper plate 87 being provided with an opening for receiving and guiding the upper end of the push button 65, which projects through an opening provided therefor in the cover 15.

A vertically disposed plate 91 is secured to the lower end of the push button 65 by having a portion thereof embedded in the insulating material of the push button. The plate 91 is provided with an elongated horizontal slot 92 which engages the knee pivot pin 77 of the toggle links, so that the push button 65 is thus connected to the toggle links. The plate 91 is also provided with a depending leg 93 which passes through an opening provided therefor in the lower guide plate 89. The guide plates 87 and 89, in addition to guiding the push button 65, also serve to limit the movement thereof by reason of the fact that the plate 91 engages the guide plate 87 in the open circuit or outer position of the push button and engages the lower plate 89 in the closed circuit or inner position of the push button 65 as best shown in Figs. 1 and 5.

The multiple arm switch lever 55 (Figs. 1 and 7) comprises an upper yoke-shaped arm 95 and a lower yoke-shaped arm 97, both arms being pivoted about a common pivot pin 99 supported by the main frame. The bridge portion 101 which bridges the legs of the lower arm 97 serves as a stop to limit clockwise rotation of the upper arm 95 with respect to the lower arm. The lower ends of the legs of the lower arm 97 are pivotally connected to the movable contact 47 by means of a pivot pin 100, the contact member being held against lateral shifting movement on the pin 100 by spacers 102 (Fig. 7).

A spring 105, which is coiled about the pivot pin 99, serves to bias and maintain the arms 95 and 97 in the extended position, as shown in Figs. 4 and 5, in which the upper arm 95 engages the bridging member 101 of the lower arm 97. A spring 107, which is coiled about the pivot pin 75 connecting the toggle links 57 with the upper arm 95 of the switch lever 55, serves to bias the toggle links 57 in a counter-clockwise direction about the pivot pin 75. It will thus be seen that the spring 107 serves to bias the toggle formed by the links 57 and 59 to their collapsed position, and the closing push button 65 to its outer open position, as shown in Figs. 4 and 5.

A spring 109, which has its ends secured to the side plates 53 of the main frame, part of its body portion coiled about the pivot pin 99, and the remaining portion engaging the upper arm 95 of the switching lever 55, serves to bias the switching lever in a clockwise direction about the pivot pin 99 to its open circuit position.

The release push button 67 is connected with the latching lever 63 by means of a release rod 111 and a pivoted transfer lever 113. The lever 113 is pivotally mounted intermediate its ends on the main frame by means of a transverse pivot pin 115 (Fig. 1). The right-hand end of the lever 113 has a reduced end portion 117 which engages in an opening provided therefor in the bearing portion 81 of the latch lever 63. The release rod 111 has the release push button

67 secured to its upper end while the lower end thereof is offset and has a reduced end portion which fits in an opening provided in the left-hand end of the transfer lever 113. The release rod 111 and push button 67 are held in mounted position by the cover 15. A biasing spring 119 engages the underside of the transfer lever 113 on the left side of its pivot pin 115. The biasing spring 119 serves to maintain the latching lever 63 in latching position in which its notched free end engages and holds the support lever 61 in normal position. The spring 119 also serves to bias the release rod 111 and the push button 67 in an upward direction to their normal position, as shown in Fig. 1. The novel manner of connecting the lower end of the release rod 111 to the transfer lever 113 and the right-hand end of the transfer lever 113 to the bearing portion 81 of the latching lever 63 eliminates the necessity of any connecting pivot pins and thus reduces the manufacturing cost of the breaker.

The manual operation of the circuit breaker is briefly as follows: With the breaker in closed position, as shown in Fig. 1, let it be assumed that it is desired to manually open the breaker. The push button 67 is manually depressed to cause downward movement of the release rod 111. The downward movement of the release rod 111 moves the transfer lever 113 in a counter-clockwise direction about its pivot pin 115. The counter-clockwise rotation of the transfer lever 113 moves the latching lever 63 in a counter-clockwise direction about its pivot pin 80 to effect release of the supporting lever 61. When the supporting lever 61 is released, the biasing force exerted by the spring 109 acting on the multiple arm switch lever 55 moves the switch lever to open circuit position to open the contacts and also moves the toggle links 57 and 59 toward the right, as viewed in Fig. 1, to partially rotate the supporting lever 61 in a counter-clockwise direction about its pivot pin 69. The slot 92 permits the knee pivot pin 77 of the toggle links to be moved to the right as the toggle links are moved to the right by the switch lever. After the switch lever 55 has been moved to open circuit position under the influence of the biasing spring 109, the force exerted by the spring 107 moves the toggle links 57 in a counter-clockwise direction about the pivot pin 75 to effect collapse of the toggle and outward movement of the push button 65, as shown in Fig. 4. This movement of the toggle to the collapsed position returns the push button 65 to its normal open circuit position and also rotates the supporting lever 61 in a clockwise direction about its pivot pin 79 to its normal position, as shown in Figs. 1 and 4. Following release of the push button 67, the biasing spring 119 acts to return the latching lever 63 to its latched position in which it re-engages the supporting lever 61. The circuit breaker is now in the open circuit position and the parts have been reset for the next circuit closing operation.

To close the breaker, the closing push button 65 is manually depressed and this movement of the push button causes the upper edge of the slot 92 to move the knee pivot pin 77 of the toggle links 57 and 59 downwardly through its dead-center position to the position shown in Fig. 1, in which the knee pivot pin 77 lies below the line joining the pivot pins 75 and 79. The movement of the toggle comprising the links 57 and 59 to its "in toggle" position moves the multiple arm switch lever 55 in a counter-clockwise direction

about its pivot pin 99 from the open position shown in Fig. 4 to the closed position shown in Fig. 1 to move the movable bridging contact 47 to closed circuit position in engagement with the stationary contacts 45. When the contacts are closed and the switch lever 55 is in the closed circuit position, the force exerted by the biasing spring 109 maintains the toggle comprising the links 57 and 59 in its "in toggle" position, since this force exerted by the spring 109 is greater than the force exerted by the spring 107 which tends to collapse the toggle.

During the circuit closing operation previously described, as the toggle comprising the links 57 and 59 is moved by the push button 65 to its "in toggle" position, the upper arm 95 of the multiple arm switch lever 55 is rotated in a counter-clockwise direction about the pivot pin 99 relative to the lower arm 97 of the switch lever. This relative movement of the upper arm 95 with respect to the lower arm 97 of the switch lever stresses the spring 105 to store energy therein. After sufficient energy has been stored in the spring 105 it moves the lower arm 97 of the switch lever in a counter-clockwise direction to closed circuit position with a snap action to close the contacts. The spring 105 also serves to maintain a predetermined contact pressure between the movable contact 47 and the stationary contacts 45 in the closed circuit position of the breaker.

During a circuit opening operation, the force exerted by the biasing spring 109 and that exerted by the biasing spring 105 moves the upper arm 95 of the switch lever in a clockwise direction about the pivot pin 99 until the legs of the lever 95 engage the bridging member 101 of the lower arm 97. During this movement, considerable kinetic energy is stored in the upper moving arm 95 so that this kinetic energy, together with the force exerted by the spring 109 on the upper arm 95 of the switch lever, moves the lower arm 97 from the closed circuit position shown in Fig. 1 to the open circuit position shown in Fig. 4 with a snap action to open the contacts.

It will be noted that the connecting means between the closing push button 65 and the knee pivot pin 77 of the toggle links renders the switch lever 55 and movable contact 47 trip-free of the closing push button. That is to say, the slot 92, which connects the push button 65 to the knee pivot pin 77 permits the switch lever 55 to be moved to open circuit position under the influence of the biasing spring 109 following release of the supporting lever 61, even though the push button 65 is manually held in the depressed position.

A thermally responsive trip means is provided for causing automatic opening of the circuit breaker in response to lower magnitude overloads of predetermined value and duration in the circuit controlled by the breaker. The thermally responsive trip means comprises a U-shaped bimetallic trip element 121 which has its legs secured to the intermediate base section 13 by means of a pair of terminal bolts 123. The upper free end of the bimetallic trip element 121 is provided with an adjusting screw 125 which engages an insulating member 124 secured to a projection on the bearing portion 81 of the latching lever 62. The insulating lever 124 serves to insulate the latching lever from the bimetallic trip element 121. The bimetallic trip element 121 when heated a predetermined amount in response to an overload of sufficient duration flexes in a direction toward the actuating mechanism. This

flexing movement of the bimetallic trip element moves the latching lever 63 in a counter-clockwise direction about its pivot pin 80 to effect release of the supporting lever 61 and opening of the breaker in the same manner as when the push button 67 is depressed.

Upon the occurrence of a heavy magnitude overload or short circuit condition in a circuit controlled by the breaker, the movable core 33 is moved upwardly by the electromagnet 25. This upward movement of the core 33 moves the thrust rod 41 in an upward direction to engage and move the transfer lever 113 in a counter-clockwise direction about its pivot pin 115. This counter-clockwise movement of the transfer lever 113 rotates the latching lever 63 in a counter-clockwise direction about its pivot pin 80 to effect release of the supporting lever 61 and opening of the breaker in the same manner as when the release push button 67 is depressed, as has been previously described.

The circuit for the breaker extends from the contact shell 19, through a conductor 127 to one terminal screw 123, through the bimetallic trip element 121 to the opposite terminal screw 123, through the stationary contact 45, movable contact 47 opposite stationary contact 45 and by means of a conductor 129 to one end of the coil 27, through the coil and from the opposite end of the coil through a conductor 131 to the center contact 21.

The side plates 53 of the frame 51, the bearing plate 49 and the spool 29 of the electromagnet 25 are all secured to the intermediate base section 13 by means of a plurality of hollow tubular rivets 133, as shown in Fig. 2. The cover or end section 15 and supporting section 17 are removably secured in clamped relation to an intermediate base section 13 by means of a plurality of bolts 135 which pass through openings 40 provided in the supporting section 17 and the cover or end section 15, the body portion of the bolts extending through the hollow tubular rivets 133. The heads of the bolts 135 engage the shoulders of the countersunk openings 137 provided in the supporting section 17, while the nuts 139 for the bolts are disposed in recesses provided in the cover or end section 15.

The base plate 49, which is secured to the upper surface of the intermediate base section 13, is provided (Fig. 9) with a pair of notched recesses 141 for receiving the legs of the lower arm 97 of the switch lever 55. The ends 143 of the recesses form stops for limiting the movement of the switch lever 55 and also function to relieve the casing 11 from any direct impact stresses during the operation of the circuit breaker.

If desired, the lowermost guide plate 89, which bridges the side walls 53 of the main frame, may be positioned a considerable distance below the dead-center position of the knee pivot pin 77, as shown in Fig. 6. The advantage of this construction is that during a manual circuit closing operation when the push button 65 is depressed a sufficient amount to move the knee pivot pin 77 below its dead-center position, the force exerted by the biasing spring 109 acts to move the knee pivot pin of the toggle downwardly until the vertically disposed plate 91, which is secured to the push button 65, engages the lowermost stop 89, so that immediately after the knee pivot pin 77 crosses dead-center position, the force exerted by the spring 109 acts to pull the push button 65 downwardly so that the latter

5 glides by and moves ahead of the finger during the circuit closing operation. This arrangement prevents false or improper operation of the circuit breaker and provides a desirable safety feature.

10 A modification of the actuating mechanism for the circuit breaker is illustrated in Fig. 5. The actuating mechanism of the modification shown in Fig. 5 is identical in all respects to the actuating mechanism described in connection with Fig. 1, except that a pivoted latch member 145 is provided for normally releasably holding the lower arm 97 of the multiple arm switch lever 55 in the open circuit position, as shown in Fig. 15 5, until the push button 65 has been moved downwardly a predetermined distance. The latch 145 is pivotally supported on the main frame by means of a pivot pin 147 and is biased to latching position by means of a spring 149. 20 The nose of the latch member 145 engages the bridging member 101, which connects the legs of the lower arm 97, when the switch lever is in the open circuit position. The tail-piece of the lever 145 is located directly below the depending 25 projection 93 which is carried by the push button 65 so that after the push button has been moved downwardly a predetermined distance the projection 93 engages the tail-piece of the latch 145, and further downward movement of the 30 push button 65 moves the latch member 145 to its released position to effect release of the lower arm 97 of the switch lever 55. The operation of this modified form of operating means is briefly 35 as follows: To close the breaker, the push button 65 is moved downwardly. During the first part of the downward movement, the toggle formed by the links 57 and 59 is moved to the "in toggle" position, as shown by the dotted lines in Fig. 5. This movement of the toggle to the extended or "in toggle" position rotates the upper 40 arm 95 of the switch lever 55 in a counterclockwise direction about the pivot pin 99 to stress and store energy in the spring 105 which connects the upper arm 95 with the lower arm 45 97. At this point of the movement of the push button 65, the depending projection 93 carried thereby engages the tail-piece of the latch member 145. Further movement of the push button 65 moves the latch member 145 in a clockwise direction about the pivot pin 147 to effect release of the lower arm 97 of the switch lever. 50 The energy stored in the spring 105 following release of the lower arm 97 moves the arm to closed circuit position with a snap action to 55 close the contacts of the breaker. This form of actuating means positively prevents improper operation of the circuit breaker, since no matter how slowly the push button 65 is depressed, the contacts are closed with a snap action when the 60 push button has been moved a predetermined amount.

It will be noted that both the supporting lever 61 and the latching lever 63 are pivotally supported at two bearing points which are spaced 65 apart a greater distance than the effective lever arms of the levers. This construction provides for greater accuracy and ease of operation of the breaker, so that larger tolerances are permissible during manufacture of the breaker. This 70 structural feature also causes the actuating means to maintain its operating accuracy for a considerably longer period of time than has heretofore been considered possible.

From the above description it will be seen 75 that the invention provides an improved circuit

breaker that is compact, safe and reliable in operation, and which can be manufactured at a relatively low cost.

While the invention has been shown and described in accordance with the provisions of the patent statutes, it is to be understood that various changes in structural details thereof may be made without departing from the spirit of the invention. It is desired, therefore, that the appended claims be given the broadest reasonable 10 construction in the light of the prior art.

I claim as my invention:

1. In a circuit breaker, a movable switch member for opening and closing the circuit, actuating means for the switch member including a 15 multiple link toggle connected at one end to the switch member and having its other end normally supported in operative position by a movable support, a movable operating member having a portion provided with a longitudinal slot 20 for engaging the knee pivot pin of the toggle which connects the operating member and toggle and provided with outer and inner shoulder portions, frame means for supporting the actuating means comprising a pair of spaced side 25 walls between which the operating member and toggle are disposed, and a pair of spaced plates extending transversely between said side walls having openings for guiding the operating member, the edges of the guide openings of said transverse plates being engageable by the shoulder portions of said operating member to limit movement thereof.

2. In a circuit breaker, a movable switch member for opening and closing the circuit, actuating means for the switch member for opening and closing the circuit including a multiple link toggle connected to the switch member at one end and engageable by a releasable lever at the other end, spring means acting on the toggle, a 40 movable push button operating member connected to the knee of the toggle for moving the toggle from collapsed position through dead-center position to a made position to close the circuit, stop means for limiting inward and outward movement of the operating member, said toggle when moved through dead-center position toward its made position acting to pull said operating member inwardly under the influence of said spring means to prevent improper closing 45 operation of the breaker, said inner stop being so positioned as to permit said push button to be pulled in through a substantial portion of the latter part of its inward movement by said toggle.

3. In a circuit breaker, a movable contact member for opening and closing the circuit, actuating means for moving the contact member to open and closed position including a pivoted double arm switch lever consisting of a pair of 60 arms pivoted about the same fixed axis, means including a spring coupling said arms for movement together, said spring tending to resiliently maintain said arms in the same predetermined 65 angular position with respect to each other at all times, one of said arms being connected with said switch member and the other with said actuating means, said actuating means including electro-responsive means operable to cause said 70 actuating means to effect circuit opening movement of said contact member.

4. In a circuit breaker, contact means for opening and closing the circuit, actuating means for opening and closing said contact means in- 75

cluding a pivoted multiple arm switch lever consisting of a pair of arms pivoted about the same axis to a fixed support, means including a spring coupling said arms for movement together, said spring acting to resiliently maintain said arms in the same predetermined angular position with respect to each other at all times, one of said arms being connected to said contact means and the other of said arms to said actuating means, 5 said spring means serving to provide a predetermined contact pressure when the contact means are closed and acting as an accelerating spring to secure quick make and break action of the contact means during operation of the breaker, 10 15 said actuating means including electroresponsive means operable to cause said actuating means to effect opening of said contact means.

5. In a circuit breaker, contact means for opening and closing the circuit, actuating means 20 for opening and closing said contact means including a pivoted multiple arm lever consisting of a pair of arms pivoted about the same axis to a fixed support, means including a spring coupling said arms for movement together, said 25 spring acting to resiliently maintain said arms in the same predetermined angular position with respect to each other at all times, one of said arms being connected to said contact means, releasable latch means for restraining said last 30 mentioned arm against closing movement when said contact means are open, a movable operating member for moving the other arm of said lever to close the circuit, said operating member having means for automatically releasing said 35 latch means to free the arm connected to said contact means at a predetermined point in the closing movement of said operating member, said actuating means including electroresponsive means operable to cause said actuating means 40 to open said contact means.

6. In a circuit breaker, relatively movable contact means, a rigid frame having spaced side walls, actuating means for opening and closing said contact means having elements thereof disposed between the side walls of said frame and connected at one end to said contact means, a lever having a U shaped bearing portion straddling the side walls of said frame and pivoted at 45 two spaced bearing points to the side walls of said frame, and having an arm disposed at the outside of one of said side walls, said lever being movable from a normal position to a tripped position to cause said actuating means to effect 50 opening of said contact means.

55 7. In a circuit breaker, relatively movable contact means, a rigid frame having spaced side walls, actuating means for opening and closing said contact means including a toggle disposed between the side walls of said frame and connected at one end to said contact means, a lever having an arm disposed adjacent one of said side walls and a U-shaped portion provided with 60 two spaced bearing portions pivoted to the side

walls of said frame to pivotally mount said lever, said lever being movable from a normal position to a tripped position to cause said actuating means and toggle to effect opening of said contact means, said spaced bearing portions of said lever being spaced apart a greater distance than the effective lever arm of said lever.

8. In a circuit breaker, relatively movable contact means, a rigid frame having spaced side walls, actuating means for opening and closing 10 said contact means including a toggle disposed between the side walls of said frame and connected at one end to said contact means, a carrier lever pivoted to said frame for supporting the other end of said toggle, said lever having a lever 15 arm disposed adjacent one of the side walls of said frame, a latching lever pivoted to said frame having a lever arm disposed adjacent said one side wall of said frame for normally engaging the 20 arm of said carrier lever to restrain said carrier lever in operative position, said carrier lever and said latching lever each having two bearing portions spaced apart a greater distance than their effective lever arms and pivoted to the spaced 25 side walls of said frame.

9. In a circuit breaker, relatively movable contact means, a rigid frame having spaced side walls, actuating means for opening and closing said contact means including a toggle disposed 30 between the side walls of said frame and connected at one end to said contact means, a carrier lever pivoted to said frame for supporting the other end of said toggle, and a latching lever pivoted to said frame for normally restraining 35 said carrier lever in operative position, said levers having lever arms normally engaged one by the other disposed at the outside of one of said side walls, and said levers each having a U shaped bearing portion straddling the side walls of said frame and pivoted to the side walls 40 of said frame at two bearing points spaced apart a greater distance than the effective lever arm of the lever, said latching lever being movable to release said carrier lever to cause opening of 45 said contact means.

10. In a circuit breaker, relatively movable contact means, a fixed frame having spaced side walls, actuating means for opening and closing said contact means having elements thereof disposed between the side walls of said frame, a pivoted latch lever movable from a latching position to an unlatched position to cause said actuating means to open said contact means, said lever having a latch arm disposed adjacent one of the side walls of said frame to one side of the actuating means, and having a U-shaped bearing portion pivotally supported at two spaced bearing points on the side walls of said frame, and means operable to apply force to the U-shaped portion of said lever between the spaced pivot points thereof to move said lever to unlatched position.

HANS H. WILLMANN.
